UNITED STATES PATENT OFFICE

90,694

DESIGN FOR A DRESSER

Sarah Laura Bennett, Oakland, Calif.

Application May 13, 1933. Serial No. 48,108

Term of patent 3½ years

To all whom it may concern:

Be it known that I, SARAH LAURA BENNETT, a citizen of the United States, and a resident of Oakland, in the county of Alameda, State of California, have invented a new, original, and ornamental Design for Dressers, of which the following is a specification, reference being had to the accompanying drawings, forming part thereof.

I claim:

The ornamental design for a dresser, as shown. In testimony of the foregoing being my own, I have hereunto affixed my signature this 25th day of February, 1933.

SARAH LAURA BENNETT.
